UNITED STATES PATENT OFFICE.

HENRY LEFEBER, OF PHILADELPHIA, PENNSYLVANIA.

BOBBIN-WINDER FOR SEWING-MACHINES.

SPECIFICATION forming part of Letters Patent No. 351,113, dated October 19, 1886.

Application filed January 6, 1886. Serial No. 187,781. (No model.)

To all whom it may concern:

Be it known that I, HENRY LEFEBER, of Philadelphia, in the county of Philadelphia, in the State of Pennsylvania, have invented a new and Improved Bobbin-Winder for Sewing-Machines, of which the following is a full, clear, and exact description.

My invention has for its object to provide a simple, inexpensive, and efficient device for 10 winding the bobbins of sewing-machines while the machine is at work, and without requiring the attention of the operator further than to place the bobbins in the winder and push a frame or lever toward the sewing-machine 15 drive wheel, and whereby the time of the operator will be economized as very little interruption of the sewing is necessary to wind the bobbins, which stop rotating automatically when they are filled.

20 The invention consists in certain novel features of construction and combination of parts of the bobbin-winder, all as hereinafter fully set forth.

Reference is to be had to the accompanying 25 drawings, forming a part of this specification, in which similar letters of reference indicate corresponding parts in all the figures.

Figure 1 is a vertical sectional elevation of my improved bobbin-winder and adjacent 30 parts of a sewing-machine to which it is attached. Fig. 2 is a front view of the winder, partly sectional, and with the spool-post and spool removed; and Fig. 3 is a plan view of the winder, partly broken away and in section.

35 The forked frame or lever A, which carries the bobbin B and drive-wheel C, is pivoted at its lower end by a pin, a, to the outer end of an arm or case, D, which is held by a screw, d, to the frame or arm E of the sewing-machine, 40 and so that the bobbin drive-wheel C may be brought into contact with the drive-wheel F of the sewing-machine. The revolving head b on the shaft of drive-wheel C has no endwise movement, but the opposite head, b', has end- 45 wise movement, and is forced forward or toward head b by a spring, b², to hold the bobbins in the frame A to be wound with thread passing from the spool G, which is placed on a pin, g', fixed to the removable cover d' of the 50 arm D. The arm D is recessed to accommodate the inner end of a trip-lever, H, which is pivoted to the arm on a pin, h, and extends

outward and carries at its outer end a plate, h', which is pressed upward against the thread being wound on the bobbin by a spring, h², 55 held on a pin, h³, in arm D, and pressing downward on the inner end or short arm of the lever.

Below the lever H is fitted so as to move endwise the rod I, which passes freely through the frame A, or between the pivot lugs thereof, and has a head, i, outside of the frame, and a spring, i', fitted at the inner end of the rod I, forces it outward when a stop-lug, i², on the rod is no longer held back by the engagement 65 with it of the back end of the lever H. (See Fig. 1.)

The thread guide or arm J, over which the thread passes from the tension-disks K K', mounted on the end of the arm A' of frame A, 70 to the bobbin B, may be attached to the inner right-hand face of the frame A, as in Fig. 1, and in full lines in Fig. 3, when the sewing-machine drive-wheel F revolves toward the operator or in direction of the arrow 1 in Fig. 75 1, the bobbin B and its drive-wheel C then rotating the other way in the direction of the arrow 2 in Fig. 1, and when the drive wheel F of a sewing-machine runs in the opposite direction to that above indicated the thread-guide J 80 will be attached at the front face and left-hand end of the frame A, holes being provided at a' to receive the attaching-screws j, which hold the thread-guide to place, and in this instance the bobbin and its drive-wheel will rotate in 85 the opposite direction to that indicated by the arrow 2, as will readily be understood. It is evident that with this reversible thread-guide J the bobbin-winder is adapted for use with 90 sewing-machines whose drive-wheels rotate either toward or from the operator.

A set-screw, L, threaded into a depending lug, d', of the arm or case D, may be turned in more or less after the holding-screw d is loosened or turned out a little, so as to swing 95 the outer end of arm D upward to carry the bobbin drive-wheel C inward bodily when in operating position against the sewing-machine drive-wheel, and whereby wear of the drive-wheel C may be taken up at any time and its 100 frictional contact with the drive-wheel F be accurately regulated.

The operation of the bobbin-winder is as follows: When the empty bobbin is adjusted

in the heads b b' , with the thread g caught in it, the frame A will be pressed inward, and when the bobbin drive-wheel C strikes the sewing-machine drive-wheel F the rod I will be pushed inward by contact of the frame A with the shoulder i^3 of the rod, and the back end of lever H will spring down in front of the lug i^2 , as in Fig. 1, to hold the wheel C to wheel F, and when the thread passing over the guide J to the bobbin fills the latter to the required extent the plate h' , which bears on the thread, will be pressed downward by the thread to lift the back end of lever H and release the rod I, which then will be forced outward by the spring i' , and its shoulder i^3 will push or swing the frame A outward and carry the drive-wheel C away from the drive-wheel F, and the pressure or friction of the lever-plate h' on the bobbin-thread will instantly stop the rotation of the filled bobbin. It is obvious that the filled bobbin is stopped automatically; hence it only is necessary for the operator to insert the bobbin in the winder and push the frame A inward, and the bobbin will be wound and stopped while the sewing-machine is at work; hence little or no time of the operator will be lost in winding the bobbins, and bobbins thus wound hold about double the quantity of thread they contain when wound by hand.

The herein-described bobbin-winder may be employed for filling bobbins to be used in silk-weaving or in knitting various fibrous yarns, or for winding the wire coils of electro-magnets, or for other analogous uses, as will readily be understood.

Having thus fully described my invention, I claim as new and desire to secure by Letters Patent—

40 1. The combination, in a bobbin-winder for sewing machines, of the frame or lever A, carrying the friction-wheel C and bobbin-

holding devices, the arm D, to which frame A is pivoted at a , the lever H, pivoted in arm D, and provided with a plate, h' , adapted to 45 bear on the bobbin-thread, a spring, h^1 , holding plate h' to the bobbin, and a rod, I, having a stop-lug, i^2 , and shoulder i^3 , and a spring 50 forcing the rod I and frame A outward, substantially as herein set forth.

2. In bobbin-winders for sewing-machines, the combination, with the arm D, carrying the lever H and rod I, and the frame A, carrying the friction-wheel C and bobbin-holding devices, substantially as specified, of an attaching-screw, d, passing freely through the lug d^2 of arm D into the sewing-machine frame E, and a screw, L, threaded into lug d^2 , and bearing against said frame E, substantially as 55 and for the purposes herein set forth.

3. In bobbin-winders for sewing-machines, the frame or lever A, provided with holes, as at a' , at opposite faces, and near the opposite journals, which support the bobbin, in combination with a reversible thread-guide, J, 65 and fastening pins or screws, substantially as described, for the purpose set forth.

4. The combination, in a bobbin-winder for sewing-machines, of the frame or lever A, carrying the friction-wheel C, and bobbin-holding devices, as at b b' , the arm D, to which frame A is pivoted at a , lever H, pivoted in arm D, and having a plate, h' , adapted to the bobbin-thread, a rod, I, having a stop-lug, i^2 , and shoulder i^3 , a spring forcing the rod I and 75 frame A outward, a spool-post, g', on arm D, an arm, A', on frame A, carrying a tension device, and fastening and adjusting screws d L, substantially as shown and described, and for the purposes herein set forth.

HENRY LEFEBER.
